SCREW DRIVER HAVING EXPANDING
SCREW HOLDING BIT

Edward L. Millen, Brookline, Mass.

Application October 11, 1945, Serial No. 621,749

1 Claim. (Cl. 145—50)

1

The present invention relates to a screw driver and particularly to the type for holding the screw by means of a gripping device provided in the end of the blade of the screw driver.

One of the difficulties encountered with screw drivers of this type is that a blade so formed is usually weakened because the blade end is not an integral piece and easily becomes bent out of alignment so that it does not operate properly particularly when spring pressure alone is relied upon for moving the blade or the tongue in the blade back to its normal position.

In the present application the tongue which produces the gripping action in the screw slot is centrally located in a recess in the blade, the recess being formed only on one face of the blade and not separating the blade into forked ends. Further, the tongue is positively moved from a position in the recess to a position out of the recess by the sliding of a collar on the shank of the screw driver.

A further advantage in the present invention is to be found in the action of the collar which is provided with considerable motion longitudinally of the screw driver shank so that a tight adjustment of the end of the blade in the screw slot may readily be obtained. The collar automatically locks the tongue in place so that the screw will be firmly retained in the end of the blade until it is properly inserted in its place.

The invention will be more fully described in connection with the embodiment described in the specification annexed hereto when taken in connection with the drawings illustrating the same in which:

Figure 1 shows a longitudinal view of the shank and blade end of the screw driver to which the present invention is applied.

Figure 2 shows a view as seen from the top of the screw driver in the position shown in Figure 1.

Figure 3 shows a section taken on the line 3—3 of Figure 2.

Figure 4 shows a section taken on the line 4—4 of Figure 1.

Figure 5 is an end view as seen from the right end of Figure 2.

In the arrangement of the figures described, 1 represents the shank of the screw driver and 2 the blade, the handle not being shown in the drawings. It will be noted that the shank and blade are slotted by a continuous slot 3 which is deeper in the central portion of its length than at its ends and forms a well or recess for receiving the adjustable or pivoted tongue element 4. 55 in the usual manner. In fact, it is customary

2

The recess 3, it will be noted, is centrally and symmetrically positioned with respect to the longitudinal axis of the screw driver throughout the shank and blade. At the end of the blade 5 the slot 3 becomes a shallow channel, as indicated by 6 in Figure 5, in which the rectangular end 7 of the tongue rests. The tongue 4 is pivoted to the blade 2 by means of a ring 8 which fits closely around the cylindrical blade 2 and passes through a hole in the blade, the hole being tangent to the surface of the blade or slightly below the surface in which case the blade may be slightly grooved to make a snug fit for the ring 8. As indicated, the upper sectional portion of 15 the ring element in Figure 3 is shown tangential to the dotted line 9 indicating the position of the surface of the blade at that point. The tongue 4 is formed with a comparatively flat edge 10 which for the most part is substantially parallel 20 with the base of the channel 3 at its bottom edge and arched by a long arch 11 at its top edge which gradually tapers with two shoulders 12 and 13 intervening before the straight portion 14 which terminates in a curved, hooked end 15. 25 The collar 16 surrounds the shank 1 and has a free sliding fit over the shank with normal allowance for longitudinal motion with respect to the blade. The collar 16 has an arched outer surface 18 adapted to fit into the curved end or hook 15 at the end of the tongue when the collar is in a position as indicated in the drawings 30 and an outwardly extending flange 17 which may serve as a grip for moving the collar. The collar may be moved from this position to the right, as viewed in Figures 1, 2 and 3, in which case it passes over the shoulder 13 and moves over the tapered surface 19 toward the shoulder 12. The movement of the collar over the shoulder 13 and the tapered surface 12 gradually raises the end 40 7 of the tongue out of the recess 6 exerting pressure against the wall of the screw slot when the end of the blade is inserted therein. The inclination of the surface 19 is such that the collar 16 will remain in the position it is put until changed 45 manually. Therefore, the screw will remain held until it is in place and released only by drawing backward the collar 16. A shoulder 12 is provided in the blade 4 to limit the motion of the collar on the blade in one direction while the curved or hooked end 15 limits the motion of the collar in the other direction. The limiting motion indicated in Figure 3 is sufficient to place the blade end completely in the recess, making 50 a smooth ended screw driver which may be used in the usual manner. In fact, it is customary

after the screw has once been inserted to pull back the collar 16 to its furthest position thereby replacing the tongue before screwing the screw down in place.

Having now described my invention, I claim:

A screw driver having a blade, the free end of which is adapted to be mounted in a screw slot, said blade having a recess formed longitudinally in it, a tongue positioned therein, means pivotally mounting said tongue on an axis perpendicular to the recess, the bottom of said recess being spaced from the bottom of the tongue, whereby the tongue may be moved about the pivot point, said tongue having a shape at the free end of the blade to form with the blade a continuous surface when the tongue is in an inward position, said tongue at the other end terminating in a hooked section with the end portion bent over the tongue and spaced from the surface of the blade and a section adjacent the hooked section flush with the surface of the blade and a further section adjacent the last mentioned section having a shoulder rising above the surface of the

blade, a collar normally positioned on the blade in said flush section, said collar having a cam shape whereby when moved under the top portion of said hook, it will engage within the hook and raise it, thereby depressing the other end of the tongue into said inward position, and when said collar is moved in the other direction it will ride on said shoulder, depressing the same to raise the other end of the tongue out of the recess.
